UNITED STATES PATENT OFFICE.

HEINRICH STEIN, OF COLOGNE, GERMANY.

ELECTROMAGNETIC SEPARATOR.

1,048,223.

Specification of Letters Patent. Patented Dec. 24, 1912.

Application filed November 28, 1908. Serial No. 464,949.

To all whom it may concern:

Be it known that I, HEINRICH STEIN, a subject of the German Emperor, and resident of 15 Klapperhof, Cologne-on-the-Rhine, Germany, have invented certain new and useful Improvements in and Relating to Electromagnetic Separators, of which the following is a specification.

The present invention relates to that kind of known apparatus for electromagnetic separation consisting of a number of magnet cores united in a system of definite shape, particularly as relates to the upper, outer or circumferential surfaces formed by the whole of the pole pieces, and by which the magnetism is brought to bear on the material for treatment, such magnet cores being each provided with a coil winding and a pole piece, and in which the material to be treated either falls directly on to a rotating magnet drum formed by the series of electromagnets arranged concentrically about the axis and each having a separate pole piece outside on the circumference and so forming a portion of the drum casing itself, or on to a separate drum or conveyer band of non-magnetic material, while the magnets remain fixed and form with their pieces a segment shaped system inside the rotating drum or a straight band shaped system inside and along the working side of the conveyer band.

In particular the invention relates to an improvement in the position and arrangement of the separate magnets forming the system and in the arrangement and shape of their acting pole pieces, whereby the magnetic attraction and consequently the efficiency of the apparatus is considerably increased, that is to say, it is possible to obtain a certain effect with a smaller number of magnets than hitherto.

Figure 1 shows, somewhat diagrammatically, a longitudinal section through the drum; and Fig. 2 shows a section through the drum, on a radial plane between the middle and end thereof.

According to the present invention the separate cores *a* are with their windings arranged horizontally at a certain distance outward from the axis, and where such is

present, from the inner drum *b*, being held parallel and free therefrom, while at the same time each pole-piece is shaped as a frame and so arranged that it incloses the corresponding magnets lengthwise as in a case, the two short upright parts of this pole piece frame being connected to the two opposite magnet core ends, while the two longer, horizontal parts of the frame taper above and below the core, that is, on the drum, lengthwise of the core and its winding, but at a fixed distance therefrom. This pole piece then forms, if the drum, as is customary, is to work by means of its outer circumference, with its external horizontal part, that is, on the side forming the drum, two ends *c*¹ and *c*² turned toward each other, proceeding from and influenced by the opposite ends of the magnet core *a*, consequently oppositely magnetized, which are insulated from each other.

In the example shown there is first fixed on the inner drum *b* a foot *e* for each magnet, carrying at one end an upright side *f* on which is fitted the magnet core *a*, while the side *f* extends upward into one end *c* of the pole piece. At the other end of the foot *e* an upright side *g* similar in size and shape to the side *f* is fitted with separately closed magnetic circuit, and suitably fastened either to the foot *e* or on the inner drum *b* or on the magnet core, which side *g* extends up forming the second similar pole-piece *c*². The two pole-pieces *c*¹ and *c*², separated from each other by a magnetic insulation *h*, supplement one another in a form similar in size and shape to the usual pole-piece. It is however assumed in the example shown in the drawing that the two pole-piece ends, which in their simplest form would abut against each other, have a special form and position by means of which special advantages are obtained. Each of the ends *c*¹ and *c*² has the shape, when seen from the outside, of a right angled triangle, so that for each magnet two such similar triangles each with its hypotenuse directed against the other, form the complete pole piece. Owing to each of the pole-piece ends tapering to a point and the points, oppositely directed, fitting between each other, the magnetic

lines of force are better collected and the action considerably strengthened. The before described arrangement of the magnets with pole-piece ends projecting toward each other 5 need not however necessarily be adopted in the simplest form thereof as shown in the drawings; but may be modified without departure from the spirit of the invention.

It is not absolutely necessary for the magnet cores *a* which in the drawing are shown 10 as arranged in the simplest and most advantageous manner, should lie parallel to the axis of the drum or ring or any other part, but they may be inclined or perpendicular thereto, or arranged inclined slightly upward or downward, or be of curved or bent shape.

While with the previously usual upright arrangement of the magnets *a* only the one 20 upper end, that is, only one pole was utilized for the magnetic action and separation, with the horizontal arrangement according to the present invention both ends 25 of the magnets are utilized, that is, two poles and along their whole length and on both sides. This forms a considerable advantage 30 of the new arrangement, which is still further increased by two pole-piece ends of opposite polarity always coming into action opposite each other.

The described arrangement of the magnets in combination with the frame shaped, divided, double ended pole-pieces of which one part *f* forms at the same time the carrier 35 for the corresponding magnets, more conveniently permits, as shown in Fig. 1, two (or even more) sets of magnets to be arranged in the direction of the length of the drum, separated from each other by insulation pieces *i*, and in this case the upright pole-piece ends *f* which carry the magnets *a* are preferably arranged in the center of the length of the drum, side by side, but separated by the insulation *i*, while the detachable pieces *g* forming the pole piece ends *c²* are then arranged on the two sides of the drum, being fitted on from the outside. The advantage is thus obtained that after removal of the piece *g* with the pole-piece end *c²* from the outside, access is given 50 to the windings of the magnets *a* and they can be examined, repaired or replaced.

The frame shape of the separate pole-pieces whereby, the magnet core *a* carried 55 by the upright piece *f* lies inside its pole-piece as in a chamber, and whereby the whole of these magnet-ring chambers unite to form a ring shaped chamber around the inner drum *b*, the same whether the drum 60 forms only such ring in the longitudinal direction, or as shown in Fig. 1 consists of two or more such rings, side by side, forms a further considerable improvement and advantage for the apparatus. This en-

ables, as shown in Fig. 2, by cutting a circular groove in the walls *f* and *g* outside the magnets *a*, that is, between these and the pole-piece ends *c¹* and *c²*, a cylindrical wall *k* of any suitable non-magnetic material, as for instance wood, brass, pasteboard and the like, to be glued and fastened between the walls *f* and *g*, in such a manner that it surrounds the magnets *a* of the ring at a certain distance and thus entirely encloses them and the space *l* between the partition *k* and the pole-piece ends *c¹* and *c²* can again be filled with a suitable watertight and non-magnetic material or metal. If the radial joints between the separate parts *g* are then filled with a suitable watertight material, or the parts *g* fastened inside to an end piece of wood or other suitable material closing the drum at both ends, then all the magnets with their windings are in a watertight chamber, while only the active 85 pole-piece ends are exposed, and it is then possible, as shown in Fig. 2, to dip the lower part of the drum in water and allow it to rotate therein, without damage to the windings. In the same way, if the magnets 90 themselves do not form a rotating drum but are used stationary as a ring or segment, a drum or transport band of non-magnetic material being carried around or past same, the lower magnets of the series, by suitably 95 arranging the wall *k* and filling up the space *l* between *k* and the pole-pieces and the radial points between the separate partition pieces *g*, can be arranged in the water and the non-magnetic drum or the transport 100 band with the material held thereon by the magnetic power, be allowed to pass through the water. In this way besides the separation of the magnetic material from the material treated, a washing of the former is 105 effected, so that when for instance earthy or sandy particles or the like, or soluble salt compounds are attached thereto these are for the most part removed and the material 110 is obtained much cleaner than was possible with previous apparatuses.

The leading of the current to and from the separate magnet windings can of course be effected in any known suitable manner and in the same way it may be arranged in 115 any known manner to alter the polarity or demagnetize all or separate magnets, or to cut them out of the circuit or the like, in particular for the purpose of throwing off or allowing to drop at a suitable position 120 the material to be treated, and for this purpose stripping appliances or the like may be arranged at the corresponding points.

What I claim as new and desire to secure by United States Letters Patent is:—

In a separating magnet, opposite poles comprising horizontal extensions, the extension of one pole being intercalated between

the extensions of the other poles, and teeth formed by serrating the proximate edges of adjoining extensions, the teeth of one extension being in alinement with the spaces 5 between the teeth of the next extension.

In testimony whereof I have hereunto signed my name this 2nd day of September,

1908, in the presence of two subscribing witnesses.

HEINRICH STEIN.
